UNITED STATES PATENT OFFICE.

LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

IGNITION DEVICE FOR INTERNAL-COMBUSTION MOTORS.

1,384,321.

Specification of Letters Patent. Patented July 12, 1921.

Application filed April 23, 1920. Serial No. 375,985.

To all whom it may concern:

Be it known that I, LEON F. HOFFMAN, a citizen of the United States, residing at Franklin, in the county of Venango and State of Pennsylvania, have invented certain new and useful Improvements in Ignition Devices for Internal-Combustion Motors, of which the following is a specification.

0 The object, construction and method of using my improved ignition device are herein set forth with sufficient clearness to enable those skilled in the respective arts to which its construction and use relate, to 5 make and use the same.

The object of this invention is, to provide an initial ignition device for oil engines, and especially that type of oil engine which employs the heavier oils for fuel, 0 and in which ignition is normally caused by the combined effect of compression and the heat of the walls of the combustion chamber.

In this type of an engine some preliminary method must be employed to effect ignition until the walls of the combustion chamber attain a sufficiently high degree of heat to cause ignition.

Heretofore such preliminary ignition has 0 usually been secured by applying extraneous heat, as the heat of a torch, to some portion of the combustion chamber, thereby imparting a sufficient degree of heat thereto to cause ignition and to continue same until 5 the heat of explosion and combustion within the cylinder has brought the walls of the combustion chamber up to their normal operating temperature.

This invention consists of a device adapted to be electrically heated to incandescence, and which may be positioned within and withdrawn from the combustion chamber of an engine at will, to effect the necessary initial ignition promptly and efficiently and 5 without the delay incident to the application of extraneous heat to the walls of the combustion chamber.

The construction whereby I attain said object is clearly illustrated in the accompanying drawings, the various figures of which are as follows:

Figure 1 is a transverse section through the combustion chamber and the surrounding walls of an oil engine showing my ignition device applied thereto, and with the

ignition coil in the operative position within the combustion chamber.

Fig. 2 is a section through the body of the ignition device showing ignition coil withdrawn from the operative position. 60

Fig. 3 is a plan view of said body.

Fig. 4 is the locking lever by means of which the device is locked in its respective positions.

Fig. 5 is a central longitudinal section 65 through the member which, as a whole, is termed the movable pole.

Fig. 6 is an elevation of said pole.

Fig. 7 is a section on line VII—VII of Fig. 6. 70

The construction here illustrated is substantially as follows:

The walls 1 of the engine cylinder, adjacent to and surrounding the combustion chamber 2, are adapted for the reception of the igniter body or casing 3 which is formed at its lower end into a chamber 4 for the reception of the coil-housing 5, when the ignition device is withdrawn to the inoperative position, as shown in Fig. 2. Within said housing 5 is contained the resistor or ignition-coil 6, which becomes incandescent when a suitable electric current passes therethrough. Said housing 5 is carried by a tubular stem 7, to the upper end of which is attached a suitable handle 8. Within said stem is inserted a conductor rod 9, to the lower end of which rod is connected the resistor or ignition coil 6; an insulating medium 10 is provided for said rod at or adjacent to the lower end thereof, and adjacent to the upper end of said rod, within the handle 8, the insulation 11 is provided. 85

The upper end of said rod 9 is secured in position by means of the screw 12, between 95 which and said handle a suitable insulating washer 13 is provided. Suitable provision is made for the attachment of an electrical conductor 14 to said screw 12.

The lower end of said housing 5 is provided with an annular flange 15, the upper portion of which is formed into a seating face 16, to coöperate with the seat 17 in the lower end of the body 3.

Said body is secured to the wall 1 in any 105 suitable way, as by bolts 18.

Stem 7 is provided with two shoulders 19 and 20, corresponding respectively to the raised and lowered positions of the movable pole. A locking lever 21, is provided for en- 110

gagement with said shoulders to lock said pole in said positions. When said movable pole is in the raised, inoperative position, it is desirable that the face 16 seat firmly upon 5 the seat 17, and for the accomplishment of this object, shoulder 19 is given a slight bevel or downward slant, and that portion 10 22 of said lever 21 which engages said shoulder, (see Fig. 4) is correspondingly beveled or wedge-shaped, so that, as it impinges upon said shoulder, it draws the pole upward and thus forms a tight joint between 15 face 16 and its seat 17, thus preventing any leakage of air, fuel or products of combustion into chamber 4 of the body 2.

An electrical conductor 14 is connected to the conductor-rod 9 in any suitable way, as previously explained. The other conductor necessary to supply a circuit may be attached to any other part of the engine. 20

The operation of my improved ignition device is as follows:—When the engine or motor is to be started, the ignition device— or movable pole—is lowered to the position 25 shown in Fig. 1, so that the ignition coil 6 is positioned within the combustion chamber 2; the electrical current is then turned on, causing coil 6 to become incandescent; the engine is then started, and said coil produces proper ignition of the fuel of the 30 motor.

The device remains in the operative position until the walls of the combustion chamber (or any other pre-determined portion of 35 the cylinder) become sufficiently heated to produce proper ignition, whereupon the device is raised to the position shown in Fig. 2; the electrical current is thereupon discontinued.

40 By a reference to the drawings, and more especially to Fig. 7, it will be noted that the chamber 5', containing the ignition coil 6, is open upon one side only. The housing 5 is so turned or positioned that this opening 45 is turned toward the point at which fuel oil enters the combustion chamber. For the purpose of securing the above position, a pin 23 is provided in the lower end of handle 8, and a corresponding socket 24 50 is provided in the upper, adjacent face of the body or casing 3.

When the device is in the lower, operative position, said pin occupies the socket 24, thus securing and maintaining the 55 proper position of said chamber 5'. The operation of the pump which supplies this fuel oil is so timed that the oil is injected into the combustion chamber at, or approximately at, the instant when ignition 60 should take place, which is at the point of highest compression; as the fuel oil enters said chamber 5' it is thereby caused to come into contact with said coil 6, thus insuring ignition at the proper instant, as well as

an instantaneous propagation of the flame 65 throughout the whole body of the mixture.

I claim the following:

1. The combination with the combustion chamber of an internal combustion motor, of an ignition device carried within the walls 70 of said chamber adapted to be operatively positioned within said chamber and withdrawn to an inoperative position without said chamber at will, and means for locking said device in both said positions. 75

2. The combination with the combustion chamber of an internal combustion motor, of a laterally positioned pocket adjacent to said chamber, an ignition device within said pocket adapted to be introduced into said 80 chamber and withdrawn into said pocket, at will, and means for locking said device in either of said positions.

3. The combination with the combustion chamber of an internal combustion motor, of a laterally-positioned pocket adjacent to said chamber, an ignition device within said pocket adapted to be introduced into said chamber and withdrawn into said pocket at will, means for locking said device in 85 either of said positions, and means excluding the gases of combustion from said pocket when said ignition device is positioned therein. 90

4. The combination with the combustion chamber of an oil engine, of a laterally-positioned pocket adjacent to said chamber, an ignition device consisting of an incandescent element adapted to occupy said pocket and to be introduced into said chamber and withdrawn therefrom at will, and means insuring contact of the fuel oil with said incandescent element as said oil enters said 95 chamber. 100

5. The combination with the combustion chamber of an oil engine, of a laterally-positioned pocket adjacent to said chamber, an ignition device consisting of an element adapted to be heated to incandescence, occupying said pocket and adapted to be introduced into said chamber and withdrawn into said pocket at will, means for heating said element, means insuring contact of the fuel oil with said element as said oil enters the combustion chamber, means manually operable to actuate said element to its respective positions within said pocket and within said combustion chamber, and means excluding the gases of combustion from said pocket when said element is positioned 110 therein. 115

In testimony whereof I affix my signature in presence of two witnesses.

LEON F. HOFFMAN.
